UNITED STATES PATENT OFFICE.

WILLIAM H. DOWNS, OF MORRISTOWN, NEW JERSEY.

TROUSERS.

1,130,966.

Specification of Letters Patent. Patented Mar. 9, 1915.

Application filed April 11, 1910. Serial No. 554,627.

To all whom it may concern:

Be it known that I, WILLIAM H. Downs, a citizen of the United States, residing at Morristown, in the county of Morris and State of New Jersey, have invented new and useful Improvements in Trousers, of which the following is a specification.

This invention relates to improvements in trousers.

10 One object of the invention is to provide a pair of trousers the fly of which is closed at its upper end so that the front upper portion of the trousers and waistband is continuous or unbroken, thus presenting a neat, 15 smooth, appearance.

Another object is to provide means whereby the closed front of the trousers is drawn back and caused to fit snugly and neatly across the front, said means also supporting 20 the trousers, thus dispensing with the use of suspenders, belts, or other supporting devices.

A further object is to provide means whereby the trousers may be quickly and 25 easily put on or taken off without opening the fly, as is necessary in trousers as now constructed.

With the foregoing and other objects in view, the invention consists of certain novel 30 features of construction, combination and arrangement of parts, as will be more fully described and particularly pointed out in the appended claim.

In the accompanying drawings, Figure 1 35 is a perspective view of the upper portion of a pair of trousers constructed in accordance with the invention. Fig. 2 is a fragmentary sectional view of the rear portion of the trousers with a part of the waistband lining 40 broken away to illustrate more clearly the construction of the elastic supporting and holding strip. Fig. 3 is a similar view with the elastic supporting strip removed and showing the eyes with which the ends of said 45 strip are adjustably connected. Fig. 4 is a perspective view of the inner side of the elastic supporting strip. Fig. 5 is a horizontal sectional view through the upper portion or waistband of the trousers.

50 Referring more particularly to the drawing, 1 denotes my improved trousers, the fly 2 of which is closed at its upper end, thereby forming a continuous or unbroken surface for the upper front portion 2^a and 55 waistband, said portion thus presenting a

smooth, neatly fitting appearance. This continuous front portion of the trousers is held in a snug fit by suitable means hereinafter described.

In order to facilitate the putting on and taking off of the trousers, the opposite sides of the same are opened down a suitable distance from the top as shown at 3, said openings being preferably in line with the side seams of the trousers. The front edges of 65 the openings 3 overlap the rear edges and said edges are normally secured together by suitable fastenings which may be in the form of buttons, hooks or resilient head and socket fastenings 4, as shown. The upper 70 ends of the openings are preferably provided with adjustable fastenings of any suitable character, but which are here shown in the form of hooks 5 adapted to be engaged with one of a plurality of eyes 6. These adjustable fastenings permit the waistband of 75 the trousers to be lengthened or shortened as desired to fit the same to the waist of the wearer.

Arranged on the inner side of the trousers, 80 and preferably beneath the waistband lining, is a strip of elastic webbing 7, the opposite ends of which are secured by flexible tabs 8 to the inner sides of the rear portion of the trousers. On the ends of the webbing 85 7 are secured hooks 9 which are adapted to be engaged with one of a plurality of eyes 10 secured to the inner side of the rear portion of the trousers near the ends of the webbing 7 and beneath the tabs 8. 90

The strip of webbing is provided for the double purpose of drawing the front portion of the trousers into close engagement with the body of the wearer, and also for supporting and holding the trousers up in 95 proper position without the use of suspenders, buttons, belts or any other supporting devices. By providing the hooks 9 and plurality of eyes 10 the ends of the webbing strip 7 can be adjusted thereby increasing 100 or decreasing the size of the waistband and upper portion of the trousers.

The strip 7 holds the waistband of the trousers in yielding engagement with the body of the wearer and prevents the trousers from slipping down, irrespective of the position of the body and, as hereinbefore stated, no other means than this strip 7 is required to support or hold the trousers 105 while being worn. 110

- By referring particularly to Fig. 5 it will be observed that the tabs 8 while flexible are non-elastic, while the webbing 7 is elastic the ends of the tabs being stitched or otherwise permanently secured to the trousers, the hooks 9, for detachably securing and adjusting the webbing, being attached to the opposite ends of the webbing, where the tabs are connected, whereby the adjustable, flexible and self-conforming fastening, thus described is always in a convenient position to be accurately adjusted and being located under the lining is completely covered and thus protected.
- 15 By providing the side openings 3, having separable fastenings, said openings may be readily opened to permit the trousers to be quickly removed or put on without necessitating the opening of the fly.
- 20 From the foregoing description, taken in connection with the accompanying drawings, the construction and operation of the invention will be readily understood without requiring a more extended explanation.
- 25 Various changes in the form, proportions and the minor details of construction may be resorted to without departing from the principle or sacrificing any of the advan-

tages of the invention as defined in the appended claim.

Having thus described my invention, what I claim is:

A pair of trousers having plackets at its opposite sides extending from its upper edge downward and provided with suitable closures, the front and rear portions of the upper end of said trousers being continuous from placket to placket, the said trousers being provided on the inner face of its rear portion with a series of longitudinally spaced eyes, and an elastic strip having flexible tabs at its opposite ends secured to the inner face of the rear portion of the trousers at points beyond both terminal eyes of the series, and hooks secured to said strip at the inner ends of said tabs, the bills of said hooks extending inwardly toward each other and adapted to be engaged with the eyes on the trousers.

In testimony whereof I have hereunto set my hand in presence of two subscribing witnesses.

WILLIAM H. DOWNS.
